(57) **CLAIM**

The ornamental design for a carton with window, as shown and described.

DESCRIPTION

FIG. 1 is a perspective view of a carton with window, showing our new design.

FIG. 2 is a front side view thereof.

FIG. 3 is a left side view thereof.

FIG. 4 is a top view thereof.

FIG. 5 is a rear side view thereof.

FIG. 6 is a right side view thereof; and,

FIG. 7 is a bottom view thereof.

The invention pertains to an ornamental design for an article of manufacture, which can be scaled to different sizes. The broken lines depict portions of the carton with window that form no part of the claimed design.
